SYSTEM OF CONTROL FOR ELECTRIC ELEVATORS

Edgar M. Bouton, Harold W. Williams, and Danilo Santini, Jersey City, N. J., assignors to Westinghouse Electric Elevator Company, Jersey City, N. J., a corporation of Illinois

Application December 23, 1937, Serial No. 181,336

20 Claims. (Cl. 172—152)

Our invention relates to control systems for electric elevators and more particularly to systems of this character in which an eddy current brake is included in the apparatus for controlling 5 the speed of the hoisting motor in operating the car.

One object of our invention is to provide a multi-speed control system by means of which an alternating current motor may be used for 10 operating an elevator car and with which a more uniform rate of deceleration to a low landing speed for the car can be obtained than is possible with other forms of alternating current drive.

Another object is to provide a control system 15 for operating an elevator embodying an alternating current driving motor for the car by means of which a greater number of stops may be made each hour without overheating the motor than is usual in either single or multi-speed alternating current drives heretofore used in elevator 20 systems.

A further object is to provide a control system having an alternating current motor drive for the car in which good speed regulation may be 25 secured with variations in load at a lower speed than is practical in other forms of multi-speed alternating current drive.

A still further object is to provide a control system for an elevator having a single speed alternating current motor for driving the car by means 30 of which the car attendant may secure intermediate speeds and an adjustable low speed or, in other words, to secure a plural speed system with a single speed motor.

35 It is also an object to provide for so controlling an eddy current brake in an elevator system having a single speed driving motor for the car that the rate of deceleration of the car may be readily adjusted and controlled to secure the most desirable results in the operation of the car.

For a better understanding of the invention, reference may be had to the accompanying drawings, in which—

45 Figure 1 is a diagrammatic representation of an elevator system with means for controlling the same in accordance with my invention, and

Fig. 2 is a key illustration of the relays and switches embodied in Fig. 1.

50 The illustration of the relays in Fig. 2 shows them with their coils and contact members disposed in horizontal alignment with their positions in the "straight line" circuits of Fig. 1, so that the reader may readily determine the position of the coil and the contact members of any relay

in the "straight line" circuit. The relays are named as follows:

CS=Car switch.	
U=Up direction switch.	5
D=Down direction switch.	
M=Control system conditioning relay.	
H=Hoisting motor.	
B=Eddy current brake.	
P=Regulator field control relay.	10
R=Regulating generator.	
S=Speed generator.	
T=Limit relay.	
V=First resistance control relay.	
W=Second resistance control relay.	15
X=Third resistance control relay.	

Referring more particularly to the drawings, we have illustrated an elevator car 16 as supported by a cable 11 passing over a hoisting drum 12 to a suitable counterweight 13. The hoisting drum is mounted upon a shaft 14 driven by an electric motor H. A suitable gear reducing mechanism 15 is connected with the shaft 14 to secure an appropriate speed of the car when the motor H is in operation. A stopping brake 17 operated 25 by an electromagnetic coil 18 is provided for stopping the car and holding it at any floor at which a stop is to be made. The brake 17 is of the electromagnetic type which is well known and will not be further described.

The hoisting motor is illustrated as a three-phase alternating current motor comprising a stator having windings 21, 22 and 23 and a wound rotor 20 having windings 24, 25 and 26. The rotor windings are connected by suitable collector 35 rings 27 through a plurality of control resistors 28 to 29.

A suitable source of alternating current electrical energy for the motor H is represented by the supply conductors L1, L2 and L3. The control system for the elevator is represented as supplied with energy through a plurality of supply conductors L+4, L-4, L+5 and L-5 which may be supplied with direct current energy from the supply conductors L1 and L3 through a plurality of suitable rectifiers 30.

The starting and stopping of the hoisting motor H is controlled by an up direction switch U and a down direction switch D which, in turn, are controlled by a master switch CS disposed in the car for operation by the car attendant. Hence, the car may be started by moving the switch CS from its center position to its up or down position and it may be stopped by returning the switch to its center or "off" position.

A conditioning relay **M** is provided for connecting and preparing certain control circuits for operation when the car is to be started and for disconnecting them when the car is to be stopped.

A first resistance relay **V**, a second resistance relay **W** and a third resistance relay **X** are provided for disconnecting the resistors **r1** to **r9** in the rotor circuit of the hoisting motor when it starts and for reconnecting them in that circuit at a desired point in decelerating the motor.

A limiting relay **T** is provided for bringing the resistance relays into effective operation and for disconnecting them from operation during certain operations of the car.

Heretofore where single speed alternating current motors have been used for operating elevators, it has been difficult to secure a flexible system for controlling the speeds of the car as desired. In order to secure a flexible system which will permit the use of a motor of this character for operating an elevator car and at the same time be able to start and stop often without overheating the motor and secure different speeds of the car at different times, we have provided a control brake, such as an eddy current brake **B**, for applying a braking effect to the car when it is being decelerated and for also holding it at certain predetermined speeds, when desired, a regulating generator **R** for controlling the energization of the brake **B**, and a speed generator for controlling the regulator in accordance with the speed of the car.

The eddy current brake **B** is provided with a rotor **30** and two field windings, the first winding being indicated as **BF4** and the second winding as **BF5**. The rotor may be either a solid iron type or a squirrel cage type, as required, to secure the torque desired and, as illustrated, is mounted directly on the shaft **16** upon which the hoisting motor **H** is mounted. The winding **BF4** passes around the pole pieces **31** and **33** and is excited by a source of electric energy represented by the supply conductors **L+5** and **L-5**. This winding is provided to furnish part of the excitation necessary to secure the braking torque desired. A resistor **r10** is disposed in circuit with the field winding **BF4** so that the value of the excitation of the winding **BF4** may be adjusted. The winding **BF5** is disposed upon the pole pieces **32** and **34** and is connected to be energized by a small regulating generator **R**. Depending upon the voltage of the regulator, the effect of the field winding **BF5** when energized will be to either buck or boost the excitation of the field winding **BF4** and thereby regulate the amount of braking torque applied by the brake **B**.

The regulator **R** is driven at a constant speed by a three phase alternating current motor **41** and it is provided with a constant field winding **RF1**, a control field winding **RF2** and a series field winding **RF6**. The motor **41** may be of any suitable three-phase alternating current type and is shown as having an armature **42** and field windings **43**, **44** and **45** which may be connected by the contact members **M1**, **M2** and **M3** to a suitable source of electrical energy as represented by the supply conductors **L1**, **L2** and **L3**. The regulator winding **RF1** is connected across the supply conductors **L+4** and **L-4** in order to secure a constant current supply of electrical energy for that winding. The accumulative series field winding **RF6** is disposed in series with the armature **36** to enhance the regulating effect of the regulator **78** and should be of such a value that the current

through it produced by the voltage of the regulator armature will produce just this amount of voltage in the armature. This series field may be weaker than the value just described in which case more effort will be required from the regulator fields **RF1** and **RF2** to produce the desired speed and the effect will be that the speed regulation at this regulated speed will not be quite as good. If desired, it is practical to omit the series field entirely, but better results will be obtained if it is used. The field winding **RF2** is connected for energization by the small direct current speed measuring generator **S** directly connected to the elevator motor shaft.

A resistor **r12** and a reactance coil **46** are disposed in circuit with the field winding **RF2** to secure a desired value of current in that field winding and to limit it to a value which will make for smooth operation of the regulator. The two field windings **RF1** and **RF2** on the regulating generator are normally set to balance each other when the brake **B** is in operation and the car is operating at the predetermined speed for which the system has been designed or adjusted.

The speed measuring generator **S** is connected to the shaft **16** and thus is operated by the motor **H** in accordance with the speed of the car. Its field winding **SF3** is connected across the supply conductors **L+4** and **L-4** in order to secure a constant current supply of electrical energy for its field. Therefore its armature **40** will supply electric energy to the field winding **RF2** of the regulator **R** directly in accordance with the speed of the elevator, thus exciting the regulator winding **RF2** in accordance with the speed of the car. Hence, it will be apparent that the output of the regulating generator, as varied by the excitation of its field winding **RF2**, will control the brake energy of the eddy current brake **B** to decelerate the car to, and hold it at, a predetermined "stopping" speed.

A resistor **r11** is disposed in circuit with the field winding **RF1** of the regulator to control the regulator to control the eddy current brake to cause the car to run at predetermined speeds. The intermediate speeds and low speed of the car will depend upon the amount of the resistance **r11** inserted in the regulator field winding. In the present instance, we have shown two values of resistance, one to secure a predetermined intermediate speed and the other to secure a predetermined low speed, the low resistance to operate the car at an intermediate speed assumed to be approximately 130 feet per minute and the higher resistance to operate the car at a low speed of approximately 30 feet per minute. Which value of resistance is used will be dependent upon the position of the car switch. Other intermediate values may be provided by tapping off the resistance at different points and connecting such points to additional contacts of the car switch.

A plurality of gate and door contact members **47** and **48** are disposed in circuit with the coils of the direction switches **U** and **D** and the conditioning relay **M** to prevent operation of the hoisting motor while the car gate or any one of the hatchway doors (not shown) is open.

The following is an assumed operation of the apparatus indicated in the drawings. It will be assumed that this apparatus is designed for operating an apartment house elevator or other elevator in which the normal high speed is approximately 300 feet per minute and that it is desired to have the car decelerate from the speed

of 300 feet per minute to a low or stopping speed of approximately 30 feet per minute at which point the hoisting motor may be deenergized and the stopping brake applied to stop the car and hold it at the floor. It will also be assumed that it may be desirable at times to cause the car to run at an intermediate speed of approximately 130 feet per minute.

It will be assumed now that the attendant on the car moves the car switch CS from its center or "off" position to its up high speed position to start the car in the up direction, as is the usual practice in the elevator art. In this position, the contact members 50, 51 and 52 are engaged by the contact member 53 of the switch CS. The closing of the contact members 53 and 50 energizes the up direction switch U and the conditioning relay M through the circuit,

L+4, 53, 50, U, M, 47, 48, L-4

The energization of the conditioning relay M closes its contact members M1 to M8, inclusive. The closing of the contact members M1, M2 and M3 connects the constant speed motor 41 to the supply conductors L1, L2 and L3, thus starting that motor to operate the regulator armature 36 at a constant speed. The closing of the contact members M5 energizes the field winding RF1 of the regulator and the closing of the contact members M6 energizes the field winding SF3 of the speed generator S. The closing of the contact members M4 energizes the field winding BF4 of the eddy current brake B. The closing of the contact members M7 also energizes the brake coil 18 of the stopping brake 17, thereby releasing that brake to permit the car to be operated by the hoisting motor H.

The connections made by the conditioning relay M have prepared the control system for operation and the closing of the contact members U1 and U2 of the energized up direction switch U energizes the field windings 21, 22 and 23 of the hoisting motor H and causes that motor to start the car upwardly. The closing of the contact members U3 and U4 also connects the field winding RF2 of the regulating generator to the armature 40 of the speed generator for operation in accordance with the upward movement of the car.

However, it will be noted that the eddy current brake is not in operation at this time because the full "on" position of the car switch CS connects the switch contact members 53 and 52, thereby energizing the regulator field control relay P through circuit

L+4, 53, 52, P, L-4

The energized relay P opens its contact members P1 and P2 thereby preventing energization of the eddy current brake field windings BF4 and BF3. Therefore, the eddy current brake is not now in operation even though the regulator generator R and the speed generator S are in full operation and ready to regulate the eddy current brake when desired.

The energized relay P also closes its contact members P3. This starts the resistance control relays V, W and X into operation to gradually cut out the resistors r1 to r0 to secure the desired acceleration of the hoisting motor H. The closing of the contact members P3 energizes the relay V by the circuit

P3, V, T1, M8, L-5

The resistance relays are time delay relays and, therefore, the relay V operates slowly to close its

contact members V1 and V2 thus shorting out the resistors r1, r8 and r9 to increase the speed of the motor H. The relay V also closes its self-holding contact members V3 and closes its contact members V4 to energize the second resistance relay W by the circuit

L+5, V4, W, T1, M8, L-5

When the delay for the relay W expires, it closes its contact members W1 and W2 thereby short circuiting the resistors r4, r5 and r6 to eliminate them from the rotor circuit of the hoisting motor H to increase its speed. The energized relay W also closes its self-holding contact members W3 and closes its contact members W4 to energize the third resistance relay X which, upon expiration of its time delay, closes its contact members X1 and X2 thereby short circuiting the resistors r1, r2 and r3 so that the hoisting motor H now runs at its full speed to operate the car at, say, 300 feet per minute.

The movement of the car switch to its up high speed position also closed the contact members 51 and 53 thereby short circuiting part of the resistance r11 out of the circuit of the regulator field winding RF1 so that, if the eddy current brake were being used, it would be regulated to control the speed of the car to approximately 130 feet per minute. However, the eddy current brake is not used while the car is at high speed and the value of this resistance at present has no effect.

It will be assumed now that the car after being operated for several floors, not shown, at the assumed speed of 300 feet per minute, is to be stopped by the car attendant at the next floor. In doing this, he will, when the car is about five feet from the floor, move the car switch from the notch or contact 52 to the notch 51 to decelerate the car to an intermediate speed of approximately 130 feet per minute when it arrives at a distance of about two feet from the floor. When the car is two feet from the floor, he will move the car switch down to the notch or contact member 53 to decelerate the car down to its landing speed of approximately 30 feet per minute when it arrives at a distance of, say, two inches from the floor. When the car is at this two inch position from the floor, the attendant will center the car switch in order to deenergize the hoisting motor and apply the stopping brake to stop the car level with the floor.

In following the above-mentioned operation, it will be seen that the movement of the car switch from its high speed position to the second notch position represented by the contact member 51 leaves the contact members 51 and 53 closed but opens the contact members 52 and 53. The contact members 51 and 53 remaining closed maintains the short circuit of a portion of the resistor r11, thereby increasing the strength of the regulator field RF1 so that the regulator will cause the eddy current brake, when connected for energization, to control the car to run at its intermediate speed of approximately 130 feet per minute. The opening of the contact members 52 and 53 deenergizes the regulator control relay P, back contact members P1 and P2 thereby connect the field winding BF4 to its constant source of supply and connect the field winding BF3 to the armature of the regulating generator R for the purpose of bringing the eddy current brake B into operation to lower the speed of the car.

The closing of the contact members **P1** also causes the limit relay **T** to be energized when the field winding **BF4** comes up to full strength and the energized relay **T** then opens its contact members **T1** thus deenergizing the resistance control relays **V**, **W** and **X** which, in turn, open their contact members **V1**, **V2**, **W1**, **W2**, **X1** and **X2** to reinsert the resistors **r1** to **r9** in the circuit of the armature **20** of the hoisting motor.

10 The insertion of these resistors in the hoisting motor circuit and the energization of the brake **B** will cause the car to decelerate to a speed of approximately 130 feet per minute by the time it arrives at a distance of about two feet from the floor. By reason of various factors, the car may run at a greater or at a less speed, but if it does, the eddy current brake will bring it into line with the desired speed.

This is effected because the insertion of the resistance into the rotor circuit causes the alternating current motor to have a drooping speed characteristic with load. We can assume that at zero speed the motor will develop a little more than full load torque and at some intermediate speed such as 130 feet per minute in the car the motor will develop full load torque. If the load on the motor is less than full load the motor will run faster until at zero load it will run at its synchronous speed. If we assume half load in the car, the motor will attempt to run at a speed of, assume, 225 feet per minute, and to obtain a speed of 130 feet per minute, it is necessary to bring the motor load up to full load. This extra load is developed by the eddy current brake.

Under the condition of full load in the car, the load alone is sufficient to bring the speed down to 130 feet per minute and no torque is required from the eddy current brake. Under these conditions coils **BF4** and **BF5** are energized equally and oppose each other and the net effect is that no flux exists in the field structure to set up a braking action. If any flux were present and some braking did occur the motor would be loaded to greater than full load and it would tend to run at a speed less than 130 feet per minute, and the voltage of generator **S** would be low, the excitation of field **RF2** would be low, and field **RF1** would predominate. The effect of this is to cause a change in the current flowing in the self-excited circuit (36—**RF6**—P2—**BF5**—36) in a direction to strengthen field **BF5** and to increase the self-excitation through field **RF6**. The increased excitation in field **BF5** opposes the flux which is causing the braking, thereby reducing the braking effect. When the braking of the eddy current brake is reduced, the motor speed is then determined by the load in the car which being full load causes the car to run at 130 feet per minute.

The conditions just described are limiting ones, and we prefer to always have some braking effort required from the brake under any operating condition so that there will be some excess torque available to cause an increase in speed if such is necessary. This condition can be obtained by inserting a little less resistance in each of the resistors connected to the collector rings of the alternating current motor.

70 If the load in the car is less than full load, for example, assume half load, then the car tends to speed up to, say, 225 feet per minute. Under this condition, the voltage of generator armature **40** will increase and field **RF2** will predominate over **RF1** and a voltage will be set

up in armature **36** (opposite to that of the previous assumption) to weaken field **BF5** so that more braking flux will be generated by field **BF4**. This braking flux will set up a braking action that will add to the load in the car and the car will slow down. As long as field **RF2** predominates over **RF1** there will be an added voltage in generator armature **36** tending to weaken the current flowing through field **BF5**. In a short time field **BF5** will be so weakened and the flux in the brake set up by field **BF4** will be so great that the brake sets up a half load drag on the motor. When this is added to the half load in the car, the load on the motor is equal to full load and its speed settles to 130 feet per minute. At this speed, fields **RF1** and **RF2** again oppose each other and no extra excitation occurs in regulator **R** and the armature **36** self excites field **RF5** to just maintain the current flowing to reduce the energization of field **BF5** to a point where field **BF4** can produce half load braking.

Assuming that we have now reached that point in the operation where the car is running at 130 feet per minute, where it is two feet from the floor at which the stop is to be made and where the attendant moves the car switch from the notch **51** down to the notch **53**. This operation opens the contact members **51** and **53** on the car switch, thereby reinserting the full amount of the resistor **r11** in the circuit of the regulator field winding **RF1**, which reduces its constant current energization to the lower predetermined value designed to cause the brake **B** to decelerate the car to a landing speed of approximately 30 feet per minute when it arrives at a distance of about two inches from the floor. Inasmuch as the current value in the field winding **RF1** has been reduced and the speed generator **S** is still operating in accordance with the speed of the car, the amount of current supplied by the armature of the speed generator to the regulator field winding **RF2** is relatively greater than the value of the current in the regulator field winding **RF1**. This causes the regulator armature **36** to alter its delivery of current to the brake winding **BF5** to produce braking torque as previously described. This braking torque causes the brake **B** to exert a strong retarding effect on the car. As the car decelerates in response to the retarding effect of the brake, it, of course, decreases the speed of the speed generator **S** which decreases its armature output to the regulator winding **RF2**.

In addition, as the speed of the hoisting motor falls, the torque output of the motor increases, and, at some point, a balance will occur which, in this particular case, is designed to occur when the car is running at a speed of approximately 30 feet per minute.

When the car arrives at the speed of 30 feet per minute, it will continue to run at that speed if the car switch is not moved, because, if it goes above that speed, it will increase the speed of the generator **S** which will cause the regulator **R** to increase the retarding effect of the brake **B**; and if it goes below that speed, the corresponding decrease in speed of the speed generator **S** will reduce the retarding effect of the brake **B** so that the car will pull back up to the desired landing speed of 30 feet per minute. In fact, the operation of the eddy current brake, the regulating generator and the speed generator will be similar to that described when they brought the car to, 75

and held it at, the intermediate speed of approximately 130 feet per minute.

However, the car attendant centers the car switch when the car is two inches from the floor for the purpose of deenergizing the hoisting motor and stopping the car level with the floor. The centering of the car switch opens the contact members 53 and 50 thus deenergizing the up direction switch U and the conditioning relay M. The deenergization of the up direction switch opens its contact members U₁ and U₂ thus stopping the hoisting motor H and the deenergized relay M opens its contact members M₇ thereby applying the stopping brake 17 to stop and hold the car level with the landing at which the stop is made. The deenergized relay M also opens its contact members M₁, M₂, M₃, M₄, M₅ and M₆ to deenergize and stop the constant speed motor 41 from operating the regulator R, to deenergize the regulator field winding RF₁, to deenergize the speed generator field winding SF₃, to deenergize the eddy current brake winding BF₄ and the limit relay T thereby deenergizing the eddy current brake and restoring the control system for its next cycle of operation in starting the car.

It should be understood that the normal high running speed of 300 feet per minute, the intermediate speed of 130 feet per minute and the landing speed of 30 feet per minute are figurative and have been assumed merely for purposes of illustrating the operation of our system. It will be apparent that any elevator engineer will be able to determine the speeds he desires in any installation and that, after these speeds are assumed, he can then readily determine the sizes of the various pieces of apparatus such as the hoisting motor, the stopping brake, the eddy current brake, the regulating generator and its driving motor, and the speed generator. It will also be understood that the sizes and values will vary in each installation and that the engineer will have to design the sizes of the field windings, etc., for such apparatus in accordance with the limits of the system being installed as usual in customary practice and in accordance with the principles disclosed in this invention.

By reason of the foregoing assumed operation, it is seen that we have provided a control system for using a constant speed alternating current motor to drive an elevator car at various speeds and that the system will bring the car to, and hold it at, predetermined speeds corresponding to the contact members or notches on the master switch employed for operating the car. In view of the fact that this system permits the use of a wound rotor motor for the elevator, it will be found that the car may be started and stopped more often than with other alternating current multi-speed systems without overheating the motor. The reason for this is that the heat which would otherwise be generated in the motor is expended in the external resistors.

Although we have illustrated and described only one specific embodiment of our invention, it is to be understood that changes therein and modifications thereof may be made without departing from the spirit and scope of the invention.

70 We claim as our invention:

1. In an elevator system for operating a car in a hatchway, a motor for operating the car, means for connecting the motor to a source of energy, an eddy current brake for the car, means for connecting said brake to a source of energy

to cause it to apply a braking effect to the car, and means responsive to the speed of the car for controlling the braking effect applied by the brake to the car.

2. In an elevator system for operating a car in a hatchway, a motor for operating the car, means for connecting the motor to a source of energy, an eddy current brake, means for connecting said brake to a source of energy to cause it to apply a braking effect to the car, a speed generator, means for operating the speed generator at a speed proportional to the speed of the car, and means for causing the output of the generator to control the braking effect of the eddy current brake on the car. 15

3. In an elevator system for operating a car in a hatchway, a hoisting motor for moving the car, an eddy current brake for controlling the speed of the car, a regulating generator for controlling the eddy current brake, a speed generator for controlling the regulating generator, and means for driving the speed generator in accordance with the speed of the car. 20

4. In an elevator system for operating a car in a hatchway, a motor for operating the car, means for connecting the motor to a source of energy, an eddy current brake provided with a plurality of windings, means for connecting one of said windings to a constant current source of energy when the brake is to be energized for 25 a braking operation of the car, and means responsive to the speed of the car for energizing another one of said brake windings in accordance with the speed of the car for controlling the braking effect of the brake. 30

5. In an elevator system for operating a car in a hatchway, a hoisting motor for moving the car, an eddy current brake for controlling the speed of the car, a regulating generator for supplying energizing energy to the brake, a motor 40 for driving the regulating generator at a constant speed, a speed generator connected to operate in accordance with the speed of the car, and means responsive to operation of the speed generator for controlling the amount of energy supplied by 45 the regulating generator to the brake for causing the brake to control the speed of the car. 35

6. In an elevator system for operating a car in a hatchway, a hoisting motor for moving the car, an eddy current brake for controlling the speed of the car, a regulating generator for supplying energy to the brake, a motor for driving the regulating generator at a constant speed, a speed generator connected to operate in accordance with the speed of the car, means responsive 55 to operation of the speed generator for controlling the amount of energy supplied by the regulating generator to the brake for causing the brake to control the speed of the car, and switch means for setting the regulating generator characteristics to cause it, when controlled by the speed generator, to control the speed of the car at the predetermined speed for which the switching means is set. 60

7. In an elevator system for operating the car 65 in a hatchway, a hoisting motor for moving the car, an eddy current brake for controlling the speed of the car, a regulating generator for supplying energizing energy to the brake, said regulator generator having a constant field winding 70 and a control field winding, a motor for driving the regulating generator at a constant speed, a speed generator connected to operate in accordance with the speed of the car, means for connecting the output of the speed generator to the 75

control field winding of the regulator for controlling the amount of energy supplied by the regulating generator to the brake for causing the brake to control the speed of the car, a switching means for controlling the constant field winding of the regulator to cause the regulator, when controlled by the speed generator output, to so control the eddy current brake as to maintain the car at the predetermined speed for which the switching means is set.

8. In an elevator system for operating a car in the hatchway, a hoisting motor for moving the car, an eddy current brake for controlling the speed of the car, a regulating generator for supplying energizing energy to the brake, said regulating generator having a series field winding for controlling its regulating characteristics, a motor for driving the regulating generator at a constant speed, a speed generator connected to operate in accordance with the speed of the car, and means responsive to operation of the speed generator for controlling the amount of energy supplied by the regulating generator to the brake for causing the brake to control the speed of the car.

9. In an elevator system for operating a car in a hatchway, a motor, means for connecting the motor to a source of electric energy to operate the car, an eddy current brake for applying a braking effect to the car, said brake having a plurality of windings, means for connecting one of said brake windings to a constant current source of energy, a regulating generator having a plurality of windings, means for operating the regulating generator at a constant speed, means for conducting the output of energy from the regulating generator to another one of said brake windings whereby the braking effect of the brake on the car will be controlled by the regulating generator, a speed generator provided with a field winding, means for operating the speed generator in accordance with the speed of the car, means for connecting the speed generator field winding to a constant current source of energy, and means for conducting the output of energy from the speed generator to the regulating generator for controlling the energy supplied by the regulating generator to the brake at a value proportional to the speed of the car.

10. In an elevator system for operating a car in a hatchway, a motor, means for connecting the motor to a source of electric energy to operate the car, an eddy current brake for applying a braking effect to the car, said brake having a plurality of windings, means for connecting one of said brake windings to a constant current source of energy, a regulating generator having a plurality of field windings including a series field winding for enhancing its regulating effect, means for operating the regulating generator at a constant speed, means for conducting the output of energy from the regulating generator to one of said brake windings to cause the braking effect of the brake on the car to be controlled by the regulating generator, a speed generator provided with a field winding, means for operating the speed generator in accordance with the speed of the car, means for connecting the speed generator field winding to a constant current source of energy, and means for conducting the output of energy from the speed generator to the regulating generator for controlling the energy supplied by the regulating generator to the brake for controlling the speed of the car to a predetermined speed.

11. In an elevator system for operating a car

in a hatchway, a motor for driving the car, an eddy current brake for applying a braking effect to the car, said brake having a first winding and a second winding, means for connecting said first winding to a constant current source of energy, a regulating generator for energizing the said second winding, said regulating generator having a constant winding and a control winding, means for driving the regulating generator at a constant speed, a speed generator having a field winding connected to a constant current source of energy, means responsive to operation of the car for driving the speed generator in accordance with the speed of the car, and means for connecting the output of the speed generator to the control winding of the regulating generator to cause the regulating generator to control the energization of the eddy current brake to bring the car to a predetermined speed.

12. In an elevator system for operating a car in a hatchway, a motor for driving the car, an eddy current brake for applying a braking effect to the car, said brake having a first winding and a second winding, means for connecting said first winding to a constant current source of energy, a regulating generator for energizing the said second winding, said regulating generator having a constant winding and a control winding, means for driving the regulating generator at a constant speed, a speed generator having a field winding connected to a constant current source of energy, means responsive to operation of the car for driving the speed generator in accordance with the speed of the car, means for connecting the output of the speed generator to the control winding of the regulating generator whereby the energy supplied by the regulating generator to the eddy current brake will be controlled in proportion to the speed of the car, a resistor associated with the constant winding of the regulating generator, and a switch for including more or less of the resistor in circuit with that field winding in accordance with the predetermined speed to which the car is to be controlled.

13. In an elevator system for operating a car in a hatchway, a motor for driving the car, an eddy current brake for applying a braking effect to control the speed of the car, said brake having a first winding and a second winding, means for connecting said first winding to a constant current source of energy, a regulating generator for supplying electric energy to said second winding, said regulating generator having a constant winding and a control winding, means for connecting said constant winding to a constant current source of energy in a constant direction, means for driving the regulating generator at a constant speed, a speed generator having a field winding connected to a constant current source of energy, means for driving the speed generator in accordance with the speed of the car, and means for connecting the output energy of the speed generator to the control winding of the regulating generator in a direction opposite to the direction of energy in said constant winding, so that the output of the regulating generator will control the energization of the eddy current brake to hold the car to a predetermined speed.

14. In an elevator system for operating a car in a hatchway, a hoisting motor for moving the car, an eddy current brake for controlling the speed of the car, a regulating generator for controlling the brake, a speed generator responsive to operation of the car for controlling the regulating generator, a switch, means responsive to

one position of the switch for connecting the hoisting motor, the brake, the regulating generator and the speed generator to sources of electric energy for starting them in operation, means responsive to another position of the switch for disconnecting the brake from its sources of energy but maintaining the motor, the regulating generator and the speed generator connected to their sources of energy, and means responsive to another position of the switch for disconnecting the brake, the hoisting motor, the regulating generator and the speed generator from their sources of energy.

15. In an elevator system for operating a car in a hatchway, a hoisting motor for moving the car, an eddy current brake for controlling the speed of the car, a regulating generator for controlling the brake, a speed generator responsive to operation of the car for controlling the regulating generator, a switch, means responsive to one position of the switch for connecting the motor, the brake, the regulating generator, and the speed generator to their sources of energy for starting them in operation, means responsive to another position of the switch for controlling the output of the regulating generator to reduce the braking effect of the brake, means responsive to another position of the switch for disconnecting the brake from its source of power to render it ineffective to apply a braking effect to the car, and means responsive to another position of the switch for disconnecting the motor, the brake, the regulating generator and the speed generator from their sources of energy.

35. 16. In an elevator system for operating a car in a hatchway, a hoisting motor for moving the car, a control brake for controlling the speed of the car, a stopping brake for stopping the car, a regulating generator for controlling the control brake, a motor for operating the regulating generator, a speed generator for controlling the regulating generator, means for operating the speed generator in accordance with the speed of the car, a switching means, and means responsive to operation of the switching means for connecting the hoisting motor, the control brake, the regulating generator, the generator motor and the speed generator to sources of electric energy and rendering the stopping brake ineffective in one position of the switching means, for controlling the output of the regulating generator to reduce the braking effect of the control brake in another position of the switching means, for rendering the stopping brake ineffective and disconnecting the control brake from its sources of power but maintaining the hoisting motor, the electro-magnetic brake, the regulating generator, the generator motor, and the speed generator connected to their sources of power in another position of the switching means, and for disconnecting the hoisting motor, the control brake, the regulating generator, the generator motor and the speed generator from their sources of electric energy and for rendering the stopping brake effective in the off position of the switching means.

65. 17. In an elevator system for operating a car in a hatchway, a hoisting motor for the car, an eddy current brake for the car, said brake having a first winding and a second winding, a regulating generator for supplying electric energy to said second winding, said regulating generator having a constant field winding and a control field winding, a motor for driving the regulating generator at a constant speed, a speed generator having a field winding, means for driving the

speed generator in accordance with the speed of the car, a switching means; and means responsive to operation of the switching means for connecting the hoisting motor, the said first winding and said second winding of the brake, the constant field winding of the regulating generator, the generator motor and the field winding of the speed generator to their sources of electric energy in one position of the switching means, for disconnecting said first winding and said second winding of the brake from their sources of electrical energy but maintaining said constant field winding, of the regulating generator, the generator motor, the field winding of the speed generator, and the hoisting motor connected to their sources of energy in another position of the switching means, and for disconnecting the eddy current brake, the hoisting motor, the generator motor, the regulating generator and the speed generator from their sources of energy in the off position of the switching means.

18. In an elevator system for operating a car in a hatchway, a hoisting motor for the car, an eddy current brake for the car, said brake having a first winding and a second winding, a regulating generator for supplying electric energy to said second winding, said regulating generator having a constant field winding and a control field winding, a resistor connected to the constant field winding, a motor for driving the regulating generator at a constant speed, a speed generator having a field winding, means for driving the speed generator in accordance with the speed of the car, a switching means; and means responsive to operation of the switching means for connecting the hoisting motor, the said first winding and said second winding of the brake, the constant field winding of the regulating generator, the generator motor and the field winding of the speed generator to sources of electric energy in one position of the switching means, for varying the effective length of the resistor in another position of the switching means, for disconnecting said first winding and said second winding of the brake from their sources of electrical energy but maintaining the constant field winding, the generator motor, the field winding of the speed generator, and the hoisting motor connected to their sources of energy in another position of the switching means, and for disconnecting the eddy current brake, the hoisting motor, the generator motor, the regulating generator and the speed generator from their sources of energy in the off position of the switching means.

19. In an elevator system for operating a car in a hatchway, a motor, means for connecting the motor to a source of electric energy to operate the car, an eddy current brake for applying a braking effect to the car, said brake having a plurality of windings, means for connecting one of said brake windings to a constant current source of energy, a regulating generator having a plurality of windings, a motor connected to operate the regulating generator at a constant speed in a constant direction, means for conducting the output of energy from the regulating generator to another one of said brake windings whereby the braking effect of the brake on the car will be controlled by the regulating generator, a speed generator provided with a field winding, means for operating the speed generator in accordance with the speed of the car and in accordance with the direction of the car, means for connecting the generator field winding to a constant current source of energy in a constant di-

- rection, means for conducting the output of energy from the speed generator to the regulating generator for controlling the energy supplied by the regulating generator to the brake at a value proportional to the speed of the car, a switch for controlling the operation of the car, and means responsive to operation of the switch in reversing the direction of the car for reversing the direction of the output of the speed generator.
- 10 20. In an elevator system for operating a car in a hatchway, a hoisting motor for the car, an eddy current brake for applying a braking effect to the car, said brake having a first winding and a second winding, means for connecting the said first winding to a constant current source of energy in a constant direction, a regulating generator having a constant winding and a control winding, means for operating the regulating generator at a constant speed, means for conducting the output of energy from the regulating gen-

erator to the second winding of the brake to energize it whereby the braking effect of the brake on the car will be controlled by the regulating generator, a speed generator provided with a field winding, means for operating the speed generator in accordance with the speed of the car, means for connecting the speed generator field winding to a constant source of energy, and means for conducting the output of energy from the speed generator to the control winding of the regulating generator to energize it in a direction opposite to the direction of energization of the constant field winding of the regulating generator so that the energy supplied by the regulating generator to the brake will be controlled by the 15 operation of the speed generator.
